ELECTRICALLY CONTROLLED REGULATING MEANS

Application filed June 17, 1930. Serial No. 461,704.

My invention relates to electrically controlled regulating means which is capable of various applications but is especially adapted for use in the controlling of the pressure in steam supply lines. The invention is designed primarily to maintain the pressure of a fluid as nearly constant as may be practicable at its point of application.

The general object of the invention is to provide regulating means of novel but of simple construction and at the same time of a character such that it is highly efficient in operation.

It also is an object of the invention to provide a regulating means for the purpose indicated wherein the parts necessary to be employed and to operate efficiently are relatively few in number and wherein also the construction is of a character such that it is not apt to get out of order and in consequence fail to operate as it should.

For a fuller and more detailed statement as to the purposes and objects of means such as constitutes my invention and as disclosed herein I refer to my pending application for Letters Patent filed December 26, 1929, Serial No. 416,734.

I shall not further amplify the objects and advantages of the invention in this portion of the specification but will proceed with a detailed description thereof wherein further objects and advantages will be pointed out specifically or else will be apparent.

In order that the invention may be readily understood and its practical advantages become apparent reference should be had to the accompanying drawings wherein I have illustrated a structure in the form at present preferred by me which embodies the invention. However, it should be understood that the invention is susceptible of embodiment in other forms of construction within the scope of the claims and that various changes in the details of construction may be made without departing from the invention or the principle thereof.

In the drawings:

Fig. 1 is a view partly in front elevation and partly in vertical section of a portion of a structure embodying my invention includ-

ing the means for controlling the operation of the structure;

Fig. 2 is a view partly in side elevation and partly in vertical section looking toward the left in Fig. 1;

Fig. 3 is a view in front elevation of a portion of the structure shown in Figs. 1 and 2;

Fig. 4 is a view in side elevation of the portion of the structure shown in Fig. 3;

Fig. 5 is a diagrammatic view showing the electric circuits which are controlled by the means shown in the preceding figures of the drawings and also showing the device or mechanism controlled thereby.

In the drawings I have shown at 1 a pipe by which steam or other fluid under pressure is supplied to a Bourdon tube 2. The steam or other fluid under pressure for supplying the power for operating a steam turbine or other structure is conveyed through pipes 3 and 4, the latter being in effect a continuation of the former, the two being connected through a valve structure at 5 which operates to control the flow of fluid through the said pipes 3 and 4.

The pipe 3 leads from a source, not shown, of fluid under pressure while the pipe 4 is located between the valve structure 5 and a steam turbine or other structure to which the fluid under pressure is being conveyed.

For satisfactory operation it is necessary that the fluid be conveyed to its point of application at substantially constant pressure hence it is the purpose of the present invention to control and regulate the pressure of the fluid in the pipe 4. To that end the latter is connected through a pipe 6 to the pipe 1, the intermediate portion of the connection, however, being omitted.

Any variation of pressure of the fluid in the pipe 4 is transmitted through the pipes 6 and 1 to the Bourdon tube 2 as a result of which the latter expands or contracts depending upon whether the pressure is increased or diminished. The result of such expansion and contraction is to cause pivotal or swinging movement of an arm 10 provided at its upper end with a pointer 11, said arm being

rigidly connected with a pivoted or rotatable rod 12 which is journaled at its opposite ends in bearings provided upon a bracket 13 supported at the front end of a projection 14 which extends forwardly from a base plate or portion 15. Connection of the arm 10 to the outer or movable end of the Bourdon tube is effected by means of a projection 16 extending toward the front which projection is provided with a laterally extending arm 17. To the latter is adjustably secured at one end a bar 18 by means of binding screws 19. The opposite inner end of the said bar 18 is provided with a pin 20 which extends toward the front of the apparatus through a slot 21 which extends lengthwise of the bar 10, as shown in the drawings.

The arm 10 is provided with a depending portion which extends beyond and below the rotatable rod 12 by which it is supported, which depending portion comprises a portion 25 of considerable width. The outer opposite ends of the portion 25 are provided with spring clips 26. The bottom edge of the part 25 is provided midway of its length with a projection 27 which also is provided with a spring clip 28. The purpose of these clips is to detachably hold and support upon the depending portion 25 the hollow receptacle 30 of a mercury contact device. The opposite outer ends of the receptacle 30 terminate in projecting portions 31 which are engaged by the clips 26. The bottom of the receptacle 30 is provided with a hollow downwardly extending projection 32 which is engaged by the clip 28. It will be seen, therefore, that the receptacle 30 is detachably held by the three clips 26 and 28 upon the portion 25 which is integral or otherwise rigidly connected with the arm 10. It may be noted that the arm 10 is rigidly connected with the rod 12.

The inner surface of the bottom of the receptacle 30, which consists of glass or other suitable insulating material, is located in the arc of a circle which is concentric with the axis of rotation of the rod 12. The receptacle contains mercury 33 which constitutes a movable contact for engaging a plurality of contacts as hereinafter will be described. The mercury is inserted into the receptacle 30 through an opening in the outer or lower end of the projection 32 after which the said opening is closed or sealed off in any known manner.

The inner surface of the bottom of the receptacle 30 being concentric with the axis of rotation of the rod 12, it follows that when the said rod together with the arm 10 and part 25 is rotated the position of the mercury remains substantially unchanged. In other words, the mercury, except that portion 34 thereof contained in the projection 32, does not change its position upon pivotal movement of the arm 10 and part 25 rigidly con-

nected therewith. By reason of this fact the inertia to be overcome during the expanding and contracting movement of the Bourdon tube is decreased whereby the sensitiveness of the device is enhanced.

As indicated, the Bourdon tube varies with variations of the pressure of the fluid in the pipe 4, the said tube expanding upon an increase of pressure and contracting upon a decrease of pressure. These movements take place within limits, as is well known.

To render the oscillatory or rocking movements of the arm 10 and part 25, which is integral therewith, effective to control the condition of the fluid pressure in the pipe 4 I have provided an electrical system for supplying electric current to a reversible motor 40 the flow of the current through the said system being controlled by the electrical contact device mounted upon the part 25. It may be noted that the reversible motor 40 is associated with the valve structure at 5 and that when it is operated in one direction it tends to close the said valve and when operated in the opposite direction it tends to open the said valve. If the fluid pressure in the pipe 4 attains a height beyond that desired the Bourdon tube expands and causes the closing of an electric circuit including the motor 40 through which the current flows in a direction to cause closing movement of the movable valve member of the valve structure 5. If the fluid pressure in the pipe 4 falls below the pressure desired a reverse action takes place.

The mercury contact member mounted on the part 25 comprises five contacts 41, 42, 43, 44 and 45. The contact 41 is centrally located with respect to the group of contacts, those numbered 42 and 43 being located on one side thereof and those numbered 44 and 45 being located on the opposite side thereof. These contacts project through and are secured to the top of the receptacle 30 and the centrally located contact 41 projects at all times into the mercury 33. When the arm 10 occupies a vertical position as shown in Fig. 1 of the drawings the other contacts are spaced from the mercury. The distance of the lower ends of the contacts 42 and 44 from the top of the mercury 33 is less than the distance of the lower ends of the contacts 43 and 45 from the top of the mercury. The contacts 43 and 45 unite in a single wire 46 having connection at 47 with wires 48 and 49. The former, 48, is connected with a contact 50 projecting through one end of an oblong oscillatable container 60 of a mercury contact, said container being mounted in a spring clip 61 supported upon the lower horizontal end portion 62 of a lever of bell crank shape the other arm 63 of which projects vertically. The said lever is pivoted at 64 upon the lower end of a link 65 comprising two parallel bars or strips, only one of which is shown, which are pivotally or swingingly supported at their upper

ends upon a stationary pivot 66. A filler or block is provided at 67 between the two bars or strips constituting the link 65 which filler constitutes a bearing for the inner end of an adjustable screw 70 which is adjustably mounted upon the upwardly extending arm 63 of the bell crank lever previously referred to. A coiled spring 71 is connected at one end to the upper end of the arm 63 and at its opposite end to a stationary pin 72. The said spring 71 is normally slightly expanded and its tendency to contract holds the inner end of the adjustable screw 70 against the filler 67.

A portion of mercury 73 within the receptacle 60 is adapted to be moved from one position to another so as to connect and disconnect the inner ends of the contacts 50 and 75 with each other. Movement of the mercury contact 73 is effected by imparting a rocking movement to the link 65 which movement is transmitted to the bell crank lever comprising the parts 62 and 63. For the purpose of causing rocking or swinging movements of the link 65 I have provided a cam wheel 76 which in the construction shown comprises four projections. However, it will be understood that the number of these projections may be increased or diminished. The cam wheel 76 is mounted upon the outer end of the shaft 78 of a motor the outline of which is indicated at 79. Electric current is supplied to the motor for causing continuous rotation thereof from the main line wires 80 and 81. Current also is supplied from these wires to a transformer 82.

A conducting wire 83 is connected at one end to the outer end of the contact 75 and at its opposite end to a binding post at 84 to which also is connected one end of a wire 85 the opposite end of which is connected to the contact 41 previously referred to.

The outer end of the contact 42 previously referred to as one of those mounted in the top of the receptacle 30 is connected by means of a conducting wire 90 to a binding post 91 which is connected by means of a conducting wire 92 to a relay indicated as a whole at 93. The opposite side of the relay is connected to the transformer through a conducting wire 94.

The outer end of the contact 44 is connected by means of a conducting wire 95 to a binding post at 96 which in turn is connected by means of a conducting wire 97 to one side of a relay indicated as a whole at 98. The opposite side of said relay is connected by a conducting wire 99 to the wire 94 and thence to the transformer 82. If the arm 10 and pointer 11 thereof occupy a vertical position as shown in Fig. 1 of the drawings the contact device including the receptacle 30 will occupy the position as shown in said figure with the several contacts 42 to 45 out of engagement with the mercury 33. It will be understood, however, that at all times the

cam device 76 is rotating and causing tilting or swinging movements of the links 65 with the bell crank lever carried thereby to alternately open and close the gap between the inner ends of the contacts 50 and 75 to connect the conducting wires 48 and 83. However, no result is accomplished by the opening and closing of the gap between the inner ends of the contacts 50 and 75 while the contact device mounted upon the portion 25 remains in horizontal position as shown in Fig. 1. Assuming, however, that the fluid pressure in the pipe 4 increases so as to cause an expansion of the Bourdon tube 2 to cause movement of the arm 10 toward the right with a corresponding reverse movement of the portion 25 rigidly connected therewith, and that the pressure has increased only sufficiently to cause sufficient tilting of the arm 10 and part 25 to cause the mercury 33 in the receptacle 30 to contact with the inner lower end of the contact 42, then the circuit from the transformer will be completed through the wires 49 and 48, contacts 50 and 75, wires 83 and 85, contact 41, the mercury 33, conducting wires 90, 92, relay 93 and wire 94 to the transformer 82. The flow of current through the relay 93 operates in known manner to close a circuit including a conducting wire 100 (leading from the line 81), conducting wire 101, through the relay 93 to conducting wires 102 and 103, the motor 40 and thence through the conductor 104 to line 80.

Assuming, on the other hand, that the fluid pressure in the pipe 4 decreases and that in consequence the Bourdon tube 2 contracts to cause pivotal movement of the arm 10 toward the left with a corresponding movement of the part 25 toward the right a sufficient distance to cause contact of the mercury 33 with the conductor 44, in the latter event current would flow from the transformer 82 through conducting wires 49 and 48, contacts 50, mercury 73, conducting wires 83 and 85, contact 41, mercury 33, contact 44, conducting wires 95 and 97 to relay 98 and from the latter through conducting wire 99 to conducting wire 94 and thence back to the transformer 82.

The flow of current through the relay 98 would operate to close in known manner a circuit including the conducting wire 100, wire 105, through the relay to conducting wire 106, thence through conducting wire 107 to the motor 40, and thence through conducting wire 104 back to one of the main supply lines of the electric system.

It will be understood that by reason of the oscillation of the holder 60 to cause movement of the mercury 73 to alternately open and close the gap between the inner ends of the contacts 50 and 75 the circuits through the relays as previously described are alternately opened and closed, so as to cause in-

ermittent operation of the motor 40 to thereby gradually adjust the movable member of the valve structure 5 to re-establish the pressure desired in the pipe 4.

If the change of pressure in the pipe 4 should be of a magnitude to cause the arm 10 and the portion 25 to oscillate through relatively great distances so as to cause the mercury 33 to contact with both of the contacts 42 and 43 or 44 and 45, depending upon the direction of oscillation, then the current would flow directly from the transformer 82 through conducting wires 49 and 46 to one or the other of the relays 93 or 98. If the tilt of the arm 10 be toward the right then the current would flow through the contact 43, thence through the mercury 33 to contact 42 and thence through the conducting wires 90 and 92 to the relay 93. So long as the mercury 33 is in contact with both of the contacts 42 and 43 the operation of the motor 40 will be continuous so as to cause a rapid re-establishment of the desired fluid pressure within the pipe 4. If the tilt should be in the opposite direction a like operation would take place.

Finally, however, after a partial return of the fluid pressure to the pressure desired, so as to cause movement of the arm 10 and part 25 to disconnect the mercury 33 from either the contact 43 or 45, as the case may be, the motor 40 will be operated intermittently during the remainder of the operation of re-establishing the fluid pressure desired within the pipe 4.

Having thus described my invention, what I claim and desire to secure by Letters Patent is:

1. Electrically controlled regulating means for maintaining a fluid at a predetermined pressure, comprising in combination an oscillatable member responsive to variations of the pressure of said fluid, a plurality of electric circuits, means actuated by said circuits for controlling and regulating the pressure of said fluid, and a mercury contact device mounted upon the said member and oscillating therewith, said contact device including a plurality of contacts one of which is at all times in contact with the mercury of the said device while other contacts on opposite sides thereof are normally out of contact with said mercury but certain of which contact with the mercury depending upon the direction of movement of the said contact device to close one or the other of the circuits controlled by the said contact device.

2. Electrically controlled regulating means for maintaining a fluid at a predetermined pressure at a selected point comprising in combination a pivoted member responsive to variations of the pressure of said fluid, a plurality of electric circuits, a contact device mounted on said member and movable therewith for opening and closing said cir-

cuits, the said contact device comprising a container the inner surface of the bottom of which is concentric with the axis of the pivotal movement of the said pivoted member, a liquid contact mounted in said container which remains practically stationary during the movements of said contact device with the said pivoted member, and a plurality of contacts mounted on said container and projecting thereinto, one of said last named contacts being continuously in contact with the said liquid contact and the others thereof out of contact with said liquid contact except when said contact device occupies a tilted position.

3. Electrically controlled regulating means for maintaining a fluid at a predetermined pressure in a container comprising in combination an oscillatable member responsive to variations of the pressure of said fluid, a plurality of electric circuits, means actuated by said circuits for controlling and regulating the pressure of said fluid, a contact device mounted upon said oscillatable member and oscillating therewith, said contact device including a container the inner surface of the bottom of which is concentric with the center of oscillation of said oscillatable member, a liquid contact element mounted in said container, a plurality of contacts supported by said container and projecting thereinto, one of said last mentioned contacts normally projecting into the said liquid contact, and couples of contacts located upon opposite sides of the last named contact and being out of contact with the said liquid contact except when said contact device is tilted, the contacts of the said couples of contacts being of different lengths and one or both of which is adapted to contact with the liquid contact depending upon the extent of tilting movement of the said oscillatable member, two of the said electric circuits being adapted to be closed through the first named contact and one or the other of the contacts nearest thereto of said couples of contacts depending upon the direction of tilt of the said container, and means for interrupting the flow of current through each of the last two named circuits, the other two of the said circuits including the contacts of the respective couples of contacts, the said other two circuits by-passing the said interrupting means.

In testimony that I claim the foregoing as my invention I have hereunto signed my name this 16th day of June, 1930.

WALTER H. J. GERBER.
